CLEANING APPARATUS FOR PIPES AND
THE LIKE

George T. Thomas, Denville, N. J.

Application July 9, 1949, Serial No. 103,887

4 Claims. (Cl. 131—244)

1

This invention relates to apparatus for cleaning bores, more particularly the bores in parts of tobacco pipes and the like.

The primary object of the invention is to provide a device for cleaning the bores in parts of tobacco pipes which become dirty through the deposit of tars and condensate derived from the tobacco which require the combined action of mechanical scrubbing and chemical solvent to effect their complete removal. The device, therefore, provides a fluid applicator combined with a scrubbing element in the nature of a brush or the like and is so constructed and arranged as to inject fluid into the pipe orifice and extract it therefrom simultaneously with the scrubbing thereof.

The present invention comprises further improvements in pipe cleaning devices of the character shown in my copending application Ser. No. 652,675 on which a patent No. 2,480,167 issued August 30, 1949.

The invention will best be understood from the following description of the present preferred embodiment thereof, taken in conjunction with the drawings in which:

Fig. 1 is an elevation of the device shown with a pipe stem in place, all parts except the bottom closure plug and scrubbing element being shown in central section;

Fig. 2 is a top plan view;

Fig. 3 is a perspective view of the bottom closure plug;

Fig. 4 is an elevation of the piston;

Fig. 5 is an enlarged detail of the end of the scrubbing element stem which engages the plug shown in Fig. 3; and

Fig. 6 is a central section through the upper part of the device showing in elevation a modification of the piston and sealing sleeve.

Referring to Fig. 1, the cleaning device comprises an elongated cylindrical fluid chamber 10, the lower end of which is internally threaded to receive the bottom closure plug 11. The plug is externally threaded at 12 and provided with an upstanding boss 14 which may be formed integrally with the plug or as a separate member attached thereto. As shown in Fig. 3, the boss 14 is provided with a horizontal slot 15 and an interconnecting vertical slot 16, each slot extending half way through the boss.

Slidably mounted in the chamber 10 is a piston 18 (Fig. 4) having a circumferential groove 19, a lower neck portion 20, and an upper neck portion 21. Mounted in the groove 19 is a fluid sealing member or piston ring 22 of resilient material such as rubber or synthetic rubber of the well-known O-ring type. The piston 18 is provided with an axial passage 24, preferably having a flared bottom 25 to facilitate the insertion therethrough of a scrubbing member, this passage preferably being of a size, at least at its up-

2

per end, to receive the reduced neck portion 28 of a pipe stem 29 having the usual bore 30. Surrounding the upper neck portion 21 of the piston is a resilient sleeve 31 of rubber or the like, somewhat longer than portion 21, this sleeve being permanently attached to the piston and being adapted to contract around the pipe stem 29, making a fluid-tight seal between it and the piston.

The piston is retained within the fluid chamber 10 by means of an apertured retaining cap 32, internally threaded to screw on the upper threaded end of the chamber 10. Cap 32 has a central circular aperture of slightly less diameter than piston 18 so that its top forms a flange 33 which engages the piston which is urged upwardly within the chamber and into contact with the flange 33 by means of a compression spring 34, the lower end of which fits around the boss 14 and the upper end of which fits around the lower neck portion 20 of the piston. The spring is preferably of such diameter in its central portion as to have but slight clearance with relation to the wall of chamber 10 so that it cannot buckle as it is compressed.

The scrubbing member which operates in the bore of the pipe part may be formed, for example, of stiff twisted wire, its stem 35 terminating in a T-head 36 which fits in the grooves 15 and 16 in the boss 14. By spacing the last few coils of spring 34 closely together to form a sleeve surrounding groove 15, as shown at 37, the T-head 36 is retained in the groove so long as the device is assembled. The upper end of stem 35 is provided with a scrubbing portion such as a brush 38 which may be made of bristles or fibres of appropriate characteristics. The brush element protrudes through the axial passage 24 in the piston when the piston is in its uppermost position, as shown in Fig. 1, so that when a pipe stem is inserted into the device the brush element is easily inserted in the bore 30 of the stem, which is then pushed down into the resilient sleeve 31 into the position shown in Fig. 1.

The construction of Fig. 6 is the same as that shown in Fig. 1 except that the axial passage 24a in the piston is of smaller diameter so that the pipe stem neck portion 28 cannot be inserted therein, in consequence of which the resilient sleeve 31a is formed, as shown in Fig. 6, so as to engage the reduced neck portion 28 of the pipe stem 29 and the upper neck portion of the piston 18a.

It is to be understood that the length of chamber 10 is such that the travel of piston 18 is sufficient to permit the passage of the scrubbing element all the way through the bore 30 of the element to be cleaned. Furthermore, the brush or other scrubbing element is so formed as not to close the bore 30 to the passage of fluid.

The device shown in Fig. 1 is operated to clean

a pipe stem as follows: The desired quantity of cleaning solution is poured into the chamber 10 through the opening in the piston, the sleeve 31 serving as a small funnel. Alternatively, chamber 10 may be partially filled with the piston and top cap removed. Preferably the casing parts of the device are made of plastic and the cylindrical wall of chamber 10 may be transparent or translucent so that the fluid level may readily be seen. The pipe stem is then placed in the position shown in Fig. 1 with the reduced neck portion 23 of the stem 29 extending into the axial passage 24 in the piston 18; and with the resilient sleeve 31 in engagement with the pipe stem 29 and the upper neck portion 21 of the piston 18; and also with the brush element 38 extending into the bore 30 of the pipe stem 29. The pipe stem is then pressed downwardly against the piston, thereby depressing the piston within the cylinder 10 against the force exerted by the spring 34; after which the pressure on the pipe stem 29 is released, and the spring 34 causes the piston 18 to rise again. Thus the brush 38 is caused to reciprocate in the bore 30 and scrub the walls thereof. At the same time fluid in chamber 10 is forced upwardly through the bore of the stem as the piston descends and is sucked back again as it ascends. This reciprocation is continued until the stem is thoroughly clean, whereupon the pipe stem is removed from the device and the contaminated cleaning solution is emptied out by inverting the device. The device illustrated in Fig. 6 operates in the same way as the device shown in Fig. 1.

The entire device is readily disassembled for washing of its parts by removing the plug 11 and cap 32. The scrubbing element stem 35 is readily removable from the base plug boss 14 after removal of the spring 34 so that it can be replaced when necessary with a new element and this feature also permit the use of a variety of different types or sizes of scrubbing elements.

The piston 18 preferably has sufficient clearance in the chamber 10 to slide freely therein and the O-ring seal 22 is so related in size to the dimensions of the cylinder and the groove 19 in the piston as to be slightly flattened between the bottom of the groove and the wall of the cylinder. The groove is preferably slightly wider than the diameter of the ring so that the ring has a slight rolling motion therein as the piston is reciprocated.

By obvious modification of the size and shape of such parts as the resilient sleeve 31 and the scrubbing element 38 the device is readily adapted to cleaning parts of the pipe other than the stem or other articles than parts of smoking pipes, such for example as pistol barrels and other articles having bores subject to contamination.

It is to be understood that the foregoing embodiments, hereinbefore described, are merely illustrative and that the invention is not limited to the details thereof but is to be construed broadly within the purview of the claims.

What is claimed is:

1. A bore cleaning device comprising, a cylindrical fluid chamber, a closure for one end of said chamber, a hollow piston reciprocable in said chamber, a compression spring positioned between said closure and said piston, an apertured retaining cap removably secured to the other end of the chamber for retaining the piston therein, a scrubbing member extending through the bore in said piston, and means attaching said scrubbing member in said closure, 75

said piston being adapted for engagement by a pipe part to be cleaned, whereby the piston can be reciprocated in said chamber by pressure applied through said pipe part in opposition to said spring.

2. A bore cleaning device comprising, a cylindrical fluid chamber, a removable closure plug for one end of said chamber, a hollow piston having an axial bore reciprocable in said chamber, a compression spring positioned between said plug and said piston and adapted to move the piston to the end of the chamber opposite from said plug, an apertured retaining cap removably secured to said opposite end of the chamber for retaining the piston therein, a scrubbing member having a stem and extending through the bore in said piston, means for anchoring said stem to said closure plug, and a resilient sealing means carried by said piston for forming a fluid-tight seal with a pipe part to be cleaned.

3. A bore cleaning device comprising, a cylindrical fluid chamber, a removable closure plug for one end of said chamber, a piston having an axial bore reciprocable in said chamber, said piston having a fluid-tight sliding engagement with said chamber, a compression spring positioned between said plug and said piston and adapted to move the piston to the end of the chamber opposite from said plug, retaining means on said opposite end of the chamber for retaining the piston therein against the action of said spring, a scrubbing member having a stem removably engageable with said plug and extending through the bore in said piston, and a sealing means carried by said piston for forming a fluid-tight seal with a pipe part to be cleaned.

4. A bore cleaning device comprising, an elongated cylindrical fluid chamber, a removable closure plug for one end of said chamber, said plug having a slotted boss extending into the chamber, a piston reciprocable in said chamber having an axial bore, a fluid sealing member carried by said piston, a compression spring positioned between said plug and said piston to move the piston to the end of the chamber opposite from said plug and having a portion surrounding the slot in said boss, an apertured retaining cap removably secured to said opposite end of the chamber for retaining the piston therein, a scrubbing member having a stem engageable in said slot and extending through the bore of said piston, and a resilient sleeve carried by said piston for forming a fluid-tight seal with a pipe part to be cleaned when positioned in alignment with the bore in said piston.
